CLAIM

The ornamental design for a pattern for doll, as shown and described.

DESCRIPTION

FIG. 1 is a perspective view of a pattern for doll showing our new design;

FIG. 2 is another perspective view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is a top plan view thereof; and,

FIG. 8 is a bottom plan view thereof.

The broken line showing the doll in FIGS. 1-8 is included for the purpose of illustrating environmental structure and forms

(Continued)

no part of the claimed design. The claim is directed to only the solid lines that form the pattern and not the surrounding surface area.

1 Claim, 6 Drawing Sheets
